VANITY CASE

Bernhard H. Krueger, New York, N. Y.

Application February 14, 1931. Serial No. 515,741

3 Claims. (Cl. 132—83)

This invention relates to new and useful improvements in toilet devices, and as herein illustrated it pertains to vanity cases of the type employed for personal wear.

5 It is the object of the present invention to improve the construction of vanity cases generally, and to provide a novel construction whereby a highly efficient and desirable vanity case may be produced at a relatively low cost.

10 A feature of the present invention resides in a novel construction whereby a cosmetic in a finely divided state may be effectively confined without sifting when carried in handbags, pocket books or pockets of the user, and which at the same time will effect a free discharge of the cosmetic when it is desired for use.

A further feature of the invention resides in the provision of a novel form of cosmetic ejector which when partially rotated, will pick up a desired quantity of finely divided cosmetic and present it upon a flat surface for application to a powder puff or similar applicator.

A further feature of the invention resides in the provision of novel means whereby to impart 25 partial rotation to the cosmetic ejector which will facilitate its rotation in one direction, but which will render turning of the ejector in the opposite direction a cumbersome and unsatisfactory operation.

30 Still another feature of the invention consists in so constructing the ejector rotating means, that it operates as a retaining means for holding a powder puff or applicator in position upon the ejector where it serves to prevent undesirable sifting of the cosmetic through the ejector.

A still further feature of the invention resides in a novel construction whereby, although the ejector is freely rotatable with relation to the powder container, it will nevertheless have a tight 40 and sift-proof contact or engagement therewith.

A still further feature of the invention resides in a novel construction whereby the body of finely divided cosmetic is held against movement relative to the container, thus insuring a picking up 45 of the cosmetic by the ejector.

Other features of the invention relate to certain novel and improved constructions, arrangements and combinations of parts hereinafter described and particularly pointed out in the claims, the advantages of which will be readily understood and appreciated by those skilled in the art.

The invention will be clearly understood from the accompanying drawing illustrating the invention in its preferred forms and the following de-

tailed description of the constructions therein shown.

In the drawing,

Figure 1 is a view in front elevation of a vanity case constructed in accordance with the present invention.

Figure 2 is a sectional view taken on the line 2—2 of Figure 1,

Figure 3 is a perspective view illustrating the vanity case in its open position,

Figure 4 is a plan view of the body portion of the vanity case with the cover removed,

Figure 5 is a view similar to Figure 4 showing the cosmetic ejector removed from the body portion of the vanity case,

Figure 6 is a detail sectional view taken on an enlarged scale illustrating the manner in which the vanity case cover is secured to the main body portion thereof,

Figure 7 is a detail horizontal sectional view on an enlarged scale illustrating the connection between the vanity case cover and the body portion of the vanity case,

Figure 8 is a detail sectional view on an enlarged scale taken on the line 8—8 of Figure 4, and illustrating the manner in which the cosmetic ejector operates to pick up a portion of the finely divided cosmetic and present it upon the flat upper face of the cosmetic ejector in order that it may be picked up by an applicator or powder puff, and;

Figure 9 is a detail sectional view on an enlarged scale illustrating a modified form of construction of cosmetic ejector.

Referring again to the drawing, a vanity case 90 constructed in accordance with the present invention comprises a main body portion 10 of any desired shape. This body portion 10 may be formed from any suitable material, but I prefer bakelite or similar material molded to the desired shape or form.

The body portion 10 of the vanity case is provided with a recess 11 which forms the cosmetic container, and the cosmetic is preferably in the form of loose powder. The recess may be formed 100 by molding at the time the body 10 is formed or in any other desired manner, and said recess is defined preferably by a flange or the like 12 which is somewhat recessed in order that a cover such as 13 may be received therein. The cover 13 is 105 hinged as at 14 to the body portion in a manner to be hereinafter described, and is retained in its closed position by means of a resilient tongue or the like 15 which as more clearly shown at 16 in Figure 2, engages a portion of the body 10 of the 110

vanity case to retain the cover in its closed position.

Means is provided for retaining the loose powdered cosmetic within the receptacle 11, and this 5 means also serves to effect a discharge of powder from the receptacle and this means will herein-after be referred to as the cosmetic ejector.

This cosmetic ejector consists of a dished member 18 having a perforated bottom wall 19, an annular vertical flange 20, and a relatively small annular flange 21 arranged at substantially right angles to the plane of the vertical wall 20. This cosmetic ejector is of the same shape as the recess 11, and is adapted for rotating movement 15 within said recess to effect an ejection of the loose powder contained in said recess. Means is provided to rotate the cosmetic ejector 18, and this means is preferably in the form of inturned operating lugs 22. These lugs 22 each have a 20 curved edge 23 and a straight edge 24 so disposed that pressure applied to the straight edge 24 will effect a rotation of the cosmetic ejector 18 in the desired direction, but application of pressure to the curved edges 23 thereof will render rotation 25 of the cosmetic ejector more or less awkward and cumbersome, thus guarding against rotation of the cosmetic ejector in the wrong direction.

As best illustrated in Figure 8 of the drawings, the perforations in the cosmetic ejector 18 which 30 are designated 25, have a portion of their peripheral wall distorted out of the plane of the bottom of the cosmetic ejector 18 as illustrated at 26 in said Figure 8. This construction provides a scoop by means of which a certain portion of the cosmetic powder is scooped upwardly through the perforations and presented upon the smooth upper surface of the cosmetic ejector as illustrated at 27 in Figure 8 thus insuring delivery of a quantity of cosmetic powder upon each rotation or 40 partial rotation of the cosmetic ejector 18.

The reference character 30 designates a powder puff or other form of powder applicator, and in the present embodiment of the invention, this applicator 30 is adapted to perform the added 45 function of closing the several perforations 25 in the cosmetic ejector, and thus prevent sifting of the powder through the cosmetic ejector when the vanity case is not in use. The applicator 30 is adapted to rest within the dished cosmetic ejector 18, and as best illustrated in Figure 3, it is retained in position by means of the inwardly projecting operating lugs 22 of the cosmetic ejector thus providing a dual function for these lugs that is they serve as operating means for rotating 50 the cosmetic ejector, and also means for retaining the applicator 30 in perforation closing position and against accidental displacement relative to the cosmetic ejector.

Means is provided to form a sift proof joint between the cosmetic ejector and the side walls of the cosmetic recess and this means is also employed to provide the necessary friction for retaining the cosmetic ejector in place against accidental displacement relative to the cosmetic recess 11. In order to accomplish the above results, I employ a relatively soft compressible body such as felt, and this felt is applied preferably in the form of a strip which is positioned around the flange 20 of the cosmetic ejector 18, and is of such dimension that when the cosmetic ejector 18 is positioned within the cosmetic recess 11, the felt body which is designated 35 in the accompanying drawing will be placed under sufficient compression to produce a sift proof joint between itself and the side wall of the cosmetic receptacle, and

also to provide sufficient friction to retain the cosmetic ejector within the recess 11 under ordinary operating conditions. I consider this construction and employment of the felt body, an important feature since it renders unnecessary the use of specially constructed mechanical means for retaining the cosmetic ejector in position in the cosmetic receptacle 11, and at the same time produces in practice, highly efficient results.

Closely adjacent the cosmetic receptacle 11, the body portion 10 is provided with a recess 40 which is preferably rectangular in shape. This recess 40 is adapted to receive a resilient member consisting of a body portion 41 having end wings or the like 42. These end wings 42 and the body portion 41 of this member are adapted to frictionally engage with the end walls and one side wall respectively of the recess 40 and this member has a resilient tongue 43 which is adapted to engage the front wall of the recess 40 as indicated at 45 in Figure 6 with a biting action and thus serve to retain the member in position in the recess 40. This resilient member has an offset portion 47, and mounted in the offset portion 47 there is a hinged pintle 48 upon which the cover 13 is pivotally mounted for movement to open and close position of the receptacle 11. This offset portion 47 is of such a size that the pintle 48 overlies the upper end of the wall 49 which is interposed between the recesses 11 and 40 as illustrated in Figure 6, 105 and this construction relieves the resilient member of any strain in a direction which would tend to force the resilient member out of the recess 40 and result in detachment of the cover 13, since any strain applied to the cover in its open position is communicated directly to the resilient member mounted in the recess 40, and since the cover does not engage the body 10 of the vanity case, the cover cannot act as a lever and thereby force the resilient member out of the recess 40. 110

It sometimes happens that the body of finely divided cosmetic under certain operations becomes very solidly packed, and rotates as a body thus defeating the desired operation of the cosmetic ejector, and to prevent this turning of the cosmetic 120 as a body within the cosmetic receptacle, I provide means preferably in the form of upstanding projections or ribs 50 formed in the bottom of the cosmetic recess 11, and these ribs preferably extend radially of the recess. It is to be understood, 125 however, in lieu of these ribs, depressions might form the same function and I, therefore, do not wish to be limited to the use of ribs or upstanding projections.

In Figure 9 I have illustrated a modified form 130 of cosmetic ejector, and in this figure, the cosmetic ejector comprises a dished member 60 the vertical or side walls of which are curved as designated 61, and a compressible material such as felt 62 is seated in the recess formed by the 135 curved walls 61.

In all forms of the invention, it is desirable that the felt body be secured to the cosmetic ejector by a suitable adhesive such as paste or glue of a type well known in this art and that the same be of such a character that it can be, when placed in position, compressed to a suitable degree to provide both friction for retaining the cosmetic ejector in position in the cosmetic receptacle of the 145 vanity case and also to provide a sift tight joint between the cosmetic ejector and the walls of the cosmetic recess.

From the foregoing it will be apparent that the present invention provides a new and novel vanity 150

case which is highly efficient, and which may be manufactured and sold at a relatively low cost.

The invention has been herein illustrated in its preferred form, but it is to be understood that the invention is not to be limited to the specific constructions herein illustrated, and that it may be practiced in other forms without departing from the scope of the appended claims.

Having thus described the invention, what is claimed as new, and what it is desired to secure by Letters Patent of the United States, is:

1. In a vanity case, a rotatable powder ejector, said ejector comprising a dished member having a side flange, and relatively small operating lugs on the upper edge of said flange, and projecting inwardly of the dished container.

2. In a vanity case, a rotatable powder ejector

comprising a dished member having a side flange, and relatively small operating lugs on the upper edge of said flange, said lugs projecting inwardly of the ejector and in spaced relation to the bottom thereof to provide means for retaining a cosmetic applicator within the dished portion of said ejector.

3. In a vanity case, a rotatable powder ejector, said ejector comprising a dished member having a side flange, and relatively small operating lugs on the upper edge of said flange, and projecting inwardly of the dished container; each of said operating lugs having one curved edge and one straight edge which edges merge together at the innermost point of the lugs.
